US0D1057089S

(12) **United States Design Patent** (10) **Patent No.:** **US D1,057,089 S**
(45) **Date of Patent:** **** Jan. 7, 2025**

(54) **ELECTRIC SPRAY GUN WITH LED LAMP**

(71) Applicant: **NINGBO CONXIN MACHINERY & ELECTRIC CO., LTD**, Ningbo (CN)

(72) Inventor: **Bosen Zhang**, Ningbo (CN)

(73) Assignee: **NINGBO CONXIN MACHINERY & ELECTRIC CO., LTD**, Ningbo (CN)

(**) Term: **15 Years**

(21) Appl. No.: **29/800,328**

(22) Filed: **Jul. 20, 2021**

(30) **Foreign Application Priority Data**

Jan. 20, 2021 (CN) 202130042315.3

(51) **LOC (15) Cl.** **23-01**

(57) **CLAIM**

The ornamental design for an electric spray gun with LED lamp, as shown and described.

DESCRIPTION

FIG. 1 is a perspective view of an electric spray gun with LED lamp showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view of the electric spray gun in a second configuration shown without the LED lamp; and, FIG. 9 is a perspective view of the electric spray gun in the first configuration shown without the LED lamp.

1 Claim, 9 Drawing Sheets
